UNITED STATES PATENT OFFICE.

THOMAS LEE, OF HOME CITY, OHIO.

SPARK-ARRESTER.

SPECIFICATION forming part of Letters Patent No. 537,048, dated April 9, 1895.

Application filed November 16, 1894. Serial No. 529,000. (No model.)

To all whom it may concern:

Be it known that I, THOMAS LEE, a citizen of the United States, and a resident of Home City, Hamilton county, State of Ohio, have 5 invented new and useful Improvements in Spark-Arresters; and I do declare the following to be a full, clear, and exact description of the invention, such as will enable others skilled in the art to which it appertains to 10 make and use the same, attention being called to the accompanying drawings, with the reference-numerals marked thereon, which form a part of this specification.

This invention relates to spark-arresters as 15 used on top of smoke-stacks for the purpose of detaining the red-hot cinders or sparks carried up by the smoke and it relates particularly to such stacks, through which in addition to the smoke, also the exhaust steam 20 from steam-engines or other sources passes out, as for instance in locomotive smoke-stacks. Most spark arresters placed on top of such smoke-stacks have proved more or less a failure, by forming too much of an impediment to the free escape of the exhaust steam which, when coming in contact with them, condenses, the resulting water by dripping back onto the rising steam, still further increasing the condensation, which in addition to the mire formed when coming in contact with the soot and cinders, also interferes with the draft.

In locomotives where the maintenance of the fire for the purpose of holding the required 35 steam-pressure in the boiler, is directly dependent on the draft produced by the steam escaping through the smoke-stack, any interference with such draft affects at once the fire and makes itself felt by a reduction of 40 the steam pressure in the boiler which lessens the working capacity of the locomotive. To lessen the deleterious effect of such interference with the draft by spark-arresters, particularly in the smoke-stacks of locomotives, 45 is the object of my invention of which the following specification contains a description, together with its operation, parts and construction, which latter is also illustrated in the accompanying drawings, in which—

50 Figure 1, is a vertical section through the smoke-stack of a locomotive provided at its upper end with my improved spark-arrester.

Fig. 2, is a sectional top-view, taken on line 2—2, of Fig. 1. Fig. 3, is a sectional detail-view taken on a line 3—3, of Fig. 1.

55

6, is a part of a suitable smoke-stack, flaring outwardly at its upper end as shown at 7. Within this upper wider part is suitably supported, preferably by suspension from rods 8, a deflector 9, being of the shape of an inverted 60 cone, and of a size sufficiently reduced to leave an annular passage 10, between it and the outwardly flaring part 7, of the smoke-stack. Within this deflector and supported on its upper edge is a separator 11, also of 65 inverted cone-shape, but of less depth than the deflector cone, so as to leave an air-space 12, between the two cones. This space is intended to serve as a non-conductor of heat and for such purpose may be left empty or be 70 packed with asbestos, mineral-wool or other similar substances. The upper end of the outflaring part 7, of the smoke-stack is turned over inwardly and down as shown at 13, the downward turn being at such an angle as to 75 guide and throw the smoke and steam rising up in and entering from passage 10, against the opposite side of separator 11, and below the upper edge of the same. By the time smoke and steam have made the required turn in their 80 passage, to enable them to enter the separator and arrived against the opposite side of the same from where they entered, the velocity of their current and their density have decreased to such an extent as to make them unable to 85 carry the cinders, thus far suspended, any farther, which latter drop, partly before and finally when coming in contact with the interior surface of the separator on which surface they slide down to an outlet pipe 14, 90 through which they pass off. Smoke and steam pass off in an opposite direction through an outlet above the separating cone. Around the upper edge of the latter is provided an inturned lip 15, which prevents any cinders, 95 after once thrown against the inner surface of the separator, from being forced back again over the upper edge of the same by the smoke rising therefrom.

Part of the steam after arriving within the 100 separator becomes condensed by reason of this latter being cooler from its exposure to the outer air, than the steam, which condensation also passes off through pipe 14. Con-

densation of the steam rising within passage 10, is prevented by deflector 9, which keeps the former from coming in contact with the cooler under surface of the separator while 5 the deflector is prevented from becoming cooled by reason of the non-conducting space 12, between the two cones. The provision of this space, obtained by the use of two cones, one within the other, prevents condensation 10 of the steam rising up in passage 10, which otherwise ensues as soon as coming in contact with the cooler under surface of cone 11. The water in dripping off from this surface would drop onto the rising steam below, thus 15 carrying the effects of condensation still further and thereby producing the objectionable consequences alluded to before.

Condensation against pipe 14, is prevented by a deflector 16, which keeps the rising 20 steam from touching said pipe and is itself prevented from becoming cooled by an air-space left between it and said pipe. Passage 10, varies in width and becomes narrower toward the top, to prevent its total area from becoming 25 too large by reason of the upwardly increasing diameter at the upper end of the stack and to retain its proper size proportional to the lower part of the latter. In the upper turn of this passage and piercing the 30 inturned part of the stack, are apertures 18, preferably narrow slits, small enough to prevent cinders to pass, but sufficiently large for steam to pass out to relieve its excessive pressure should it occur and cause possibly a 35 choking of the passage at this point.

Part of the smoke and steam within cone 11, escapes occasionally downwardly through pipe 14, whereby the ready discharge of the separated cinders is assisted. Vapors so diverted are prevented however from passing clearout through pipe 14, by a flue 17, with an enlarged mouth, which intercepts their passage and conducts them back again to the top of the stack, where they join the general 45 outlet.

As will be seen, a spark-arrester built in conformity with the explained construction prevents its interior parts from becoming cooled in a manner to cause condensation 50 and thereby the objectionable effect of the latter upon the draft is avoided.

Having described my invention, I claim as new—

1. In a spark-arrester, the combination of 55 the upper, outwardly flaring part of the smoke-stack, having its upper end turned in as shown, a cone 9, supported within this part of the stack and below its upper inturned end, being of sufficiently reduced size to produce an annular 60 passage between it and the stack, to permit smoke and steam to pass up and over its upper edge and depending with its closed point into the narrowing part of the stack to deflect and divert the rising smoke and steam into 65 and over all parts of said annular passage, a cone 11, supported point downward within cone 9, and with its upper edge closely con-

nected to the latter, but of less depth than the same, to produce an inclosed space 12 completely surrounding the under-surface of cone 70 11, which serves as a non-conductor of heat and by preventing cooling of the upper or inner surface of cone 9, obviates condensation on the under-surface thereof, an outlet for smoke and steam and an outlet for cinders 75 precipitated within cone 11.

2. In a spark-arrester, the combination of the upper outwardly flaring part of the smoke-stack, two inverted cones 9 and 11, one within 80 the other and connected at their edges, suspended therein, being of equal diameters but of different depths, whereby an air space is formed between them which prevents steam from coming in contact with the under-surface of cone 11, an annular smoke-passage discharging the smoke into the inner cone, an outlet above the latter and an outlet in its lower end for the cinders. 85

3. In a spark-arrester, the combination of the upper outwardly flaring part of the smoke-stack, a separating chamber 11, suspended 90 within this upper part, to receive the separated cinders, an annular passage for the rising smoke between this chamber and the outwardly flaring part of the smoke-stack, such 95 passage being completely separated and insulated throughout its entire height from chamber 11, by a completely closed air-space which intervenes between the two and is of even height with the passage. 100

4. In a spark-arrester, the combination of the upper, outwardly flaring part of the smoke-stack, having its upper end turned in and partly down as shown, a deflecting cone 9, supported within this part of the stack and below 105 its upper inturned end, being of sufficiently reduced size to produce an annular passage between it and the stack to permit smoke and steam to pass, a separating cone supported above this latter cone which receives the vapors rising in aforesaid annular passage, and is of reduced size to produce a space between the two cones whereby condensation below the upper cone is prevented, an outlet for vapors above the latter, an outlet pipe 14, for cinders 110 in its lower part passing out through the deflecting cone and the smoke-stack and a deflector below said pipe to prevent condensation 115 on its under-surface. 120

5. In a spark-arrester, the combination of the upper, outwardly flaring part of the smoke-stack, having its upper end turned in and partly down as shown, a deflecting cone 9, supported within this part of the stack and below 125 its upper inturned end, being of sufficiently reduced size to produce an annular passage between it and the stack to permit smoke and steam to pass, a separating cone supported above it, receiving the discharge from aforesaid passage and being of reduced size to produce a space between the two cones whereby condensation on the under-surface of the upper cone is prevented, an outlet for vapors above the latter, an outlet for cinders passing 130 135

out from its lower part and a flue 17, which prevents any vapors from passing out through said lower outlet and conducts them back to the general outlet above.

- 5 6. In a spark-arrester, the combination of the upper, outwardly flaring part of the smoke-stack, two inverted cones 9, and 11 supported within this part, an annular passage 10, between them and the wall of the stack, the upper end of the stack being turned over and in above the upper ends of the cones as shown at 13, to conduct the discharge from passage 10, into the upper one of the cones, apertures

18, in this inturned end of the smoke-stack to relieve possible excess of steam pressure 15 and prevent choking in this turn of passage 10, a closed space 12, between cones 9, and 11, to prevent transmission of heat, a central outlet above the upper cone and an outlet from the lower part thereof. ²⁰

In testimony whereof I hereunto set my hand in presence of two witnesses.

THOMAS LEE.
